UNITED STATES PATENT OFFICE.

HENRY L. FERRIS, OF HARVARD, ILLINOIS.

WIRE CHAIN-LINK.

SPECIFICATION forming part of Letters Patent No. 562,519, dated June 23, 1896.

Application filed March 21, 1896. Serial No. 584,209. (No model.)

To all whom it may concern:

Be it known that I, HENRY L. FERRIS, of Harvard, in the county of McHenry and State of Illinois, have invented certain new and useful Improvements in Wire Link Chains; and I do hereby declare that the following is a full, clear, and exact description thereof, reference being had to the accompanying drawings, and to the letters of reference marked thereon, which form a part of this specification.

This invention relates to improvements in links for wire chains; and it has for its object the production of a novel form of link made from a single piece of wire, at once simple, strong, and durable, and less liable to become distorted or twisted in use than similar links as heretofore commonly constructed.

The invention consists in the matters hereinafter described, and more particularly pointed out in the appended claims, and will be readily understood by reference to the accompanying drawings, in which—

Figure 1 is a view of the wire blank from which the link is formed. Fig. 2 is a view of the same after the S-shaped bend, constituting the first step in forming the link, has been made. Fig. 3 is view of the blank after the loops have been formed and before the terminal ends of the blank have been fastened. Fig. 4 is a plan view of the completed link. Fig. 5 is a perspective view of the same. Fig. 6 is a sectional view of the completed link, taken upon line 6 6 of Fig. 4, the direction of view being indicated by the arrows thereon.

Referring to said drawings, A designates as a whole the blank which may be successively bent or shaped to bring it to its required final form, as follows:

The straight blank A is first bent between its ends to form an S-shaped portion about midway of its length. The ends a' a² of the blank project oppositely therefrom and parallel with each other, being separated laterally by a distance equal to the full width of the finished link, or, in other words, with the S-shaped portion arranged transversely with relation to the general direction of the blank, as shown in Fig. 5. Preferably, and as shown in the present instance, the bend a³ a⁴, form-

ing the S-shaped portion of the link, will be relatively deep, as shown. Each of the said portions a' a² of the blank is next bent upon itself about midway of its length to form loops (designated as a whole by A' A², respectively) 55 arranged to extend in the same plane. The end parts a' a² are each again bent at a point b a short distance from their extreme ends, and in a direction at right angles to the general plane of the link, the bends being in opposite directions to each other. Each of the right-angled portions a⁵ a⁶ thus formed is inserted through the bend of the S-shaped part opposite to and curved reversely from that part of which said end forms a continuation— 65 that is to say, the end portion a⁵ is inserted through the bend a⁴, and the end portion a⁶ is inserted through the bend a³, as clearly indicated in Fig. 3. Each of the terminal ends a⁵ a⁶ is next bent over laterally so as to extend across the link and engage the opposite member of the adjacent loop, about which said member the extreme end is finally coiled, as indicated at a⁷ a⁸. Owing to the fact that the bends of the S-shaped portion are relatively deep, the parts a⁵ a⁶ will extend across the link at points some distance apart, and substantially parallel with each other.

A link constructed in accordance with the foregoing description possesses important features of advantage. The peculiar manner in which the different parts of the link are interlocked, as described, renders the link extremely rigid at its central part, so that it is exceptionally well adapted to resist torsional 80 strains, which might tend to twist the link as a whole. At the same time, the construction is such that the transverse parts of the link constitute a pair of cross-bars, with either or both of which a hook or other fastening device 90 may be engaged, without injury to or distortion of the link, in the event of its being desirable to lengthen or shorten the chain a distance equal to one-half of a single link. A link constructed as above described, furthermore, presents a smooth exterior well adapted to run through guides without interference, or over a guide-pulley or the like. At the same time, the construction is such as to enable the link to sustain an endwise strain 95 100

thereon practically equal to the maximum strength of the wire without injury to the link.

What I claim as my invention is as follows:

- 5 As a new article of manufacture, an elongated link formed of a single piece of malleable metal comprising an S-shaped part, a loop formed in continuation of each end thereof, the terminal end of each loop being passed 10 through that bend or loop of the S-shaped part opposite the one of which it forms a continuation then extended transversely across

the middle part of the S-shaped portion and finally coiled around its own opposite side member, substantially as set forth. 15

In testimony that I claim the foregoing as my invention I affix my signature, in presence of two witnesses, this 24th day of February, A. D. 1896.

HENRY L. FERRIS.
